UNITED STATES PATENT OFFICE.

LOUIS WOJIDKOW, OF BROOKLYN, NEW YORK.

DESIGN FOR A CRUMB-SCRAPER.

SPECIFICATION forming part of Design No. 26,699, dated March 2, 1897.

Application filed January 25, 1897. Serial No. 620,703. Term of patent 31 years.

To all whom it may concern:

Be it known that I, LOUIS WOJIDKOW, a citizen of the United States, residing at Brooklyn, in the county of Kings and State of New York, have invented and produced a new and original Design for Crumb-Scrapers, of which the following is a specification, reference being had to the accompanying drawings, in which—

Figure 1 is a plan view of the crumb-scraper. Fig. 2 is a sectional view on the line 2-2 of Fig. 1.

The leading feature of my design consists of a raised scroll-like border extending around three sides or edges of the tray, the two outer scrolls forming compound curves and joining with the upper or central scrolls.

Referring to the drawings, A A represent the central and B B the outer scrolls, raised or struck up from the bottom C of the scraper ²⁰ and having their edges D bent or turned over, as shown. The outer scrolls form compound curves and join with the central scrolls at a a. E represents a handle.

What I claim is—

The design for a crumb-scraper, as herein shown and described. ²⁵

LOUIS WOJIDKOW.
